ELECTRICAL CONTROL BOARD

Raymond T. Pierce, Millburn, N. J., assignor to
 Weston Electrical Instrument Corporation,
 Newark, N. J., a corporation of New Jersey

Application June 14, 1932, Serial No. 617,176

8 Claims. (Cl. 175—298)

This invention relates to control boards for electrical apparatus, and particularly to assemblies of miniature indicating instruments and control devices.

In the development of the electrical industries, the panel board assemblies of indicating instruments and control devices have so increased in size that it is difficult to maintain a close supervision over the several generators, motors and other units. It has been proposed to substitute miniature instruments and relay control devices for the larger size units customarily mounted on the large slate panels, but the design of such miniature control units has followed the established practice for the construction of full size panel assemblies, i. e., the miniature control units have been individually constructed on panels of a size and shape determined by the number of instruments required for each particular power plant or generator system.

According to the present invention, the indicating and control devices for each individual machine of an electrical plant are mounted, in vertical alignment, on a steel rack or skeleton strip to constitute a narrow panel. The edges of the panel strips for a plurality of machines may be connected to form a control board that may be readily increased or decreased in size as machines are added to or taken from the plant.

An object of the invention is to provide a simple, economical and compact panel board in which the panel board is formed as a plurality of unit panel strips. An object is to provide a control panel strip in which a plurality of indicating and control units are assembled on a rack to constitute the panel.

A further object is to provide a panel strip of the type stated in which all of the separate units may be inserted or removed from the front of a skeleton frame, and in which all calibration tests may be made from the front of the panel.

These and other objects of the invention will be apparent from the following specification when taken with the accompanying drawings in which:

Fig. 1 is a front elevation of a typical control board assembly of two panel units,

Figs. 2 and 3 are fragmentary front and rear elevations, respectively, showing one indicating instrument on the panel strip,

Fig. 4 is a fragmentary side elevation, with parts in section, of one instrument on the supporting rack,

Fig. 5 is a top plan view of one panel strip,

Fig. 6 is a typical circuit diagram of the wiring of a panel strip, and of the connections be-

tween the panel strip and a three phase power transmission line, as viewed from the back of the panel.

Fig. 7 is a front elevation of a connecting panel unit, with the several instruments and a test set for calibration thereof shown diagrammatically, and

Fig. 8 is a fragmentary perspective view of the rear face of the cover plate for a connecting panel.

In the drawings, the reference numeral 1 identifies the skeleton frames or steel racks which are provided with large rectangular apertures for receiving indicating and control units that are of such size, viewed in elevation, as to constitute substantially the entire exposed face of the panel strip. The openings are all of the same size, and all indicating and control units are interchangeable as to size and mounting, thus permitting any desired arrangement on the front of the rack. In the preferred arrangement, the indicating instruments 2 are mounted in the upper openings, then the panels 3 that carry relay control switches and signal lights 5, and connecting panels are located in the bottom openings, being protected by cover plates 6. In general, a maximum of six instruments will be required for indicating the operation of any electrical unit and the frames are therefore provided with eight openings. For uniformity, all frames are preferably made of the same size and, when less than six instruments are required, the openings in which no instruments are mounted will be covered by dummy plates 7.

As shown in Figs. 2 to 5, inclusive, the instrument covers 8 and cases 9 are of rectangular form. The forward flanged edges of the metallic cases 9 rest against the edges of the openings in the frame 1 when the cases are inserted from the front of the frames. The corners of the flanges of cases 9 have bolts 10 welded or otherwise secured in apertures therein, the bolts extending rearwardly to project through the frame and having countersunk and threaded heads for receiving the screws 11 that secure the cover plates 8 in place. The instrument movements 12 are removable and insertable from the front of the panel assembly, and are fixed to the cases by screws 13 that pass through the rear walls of the cases.

The instrument terminals 14 are secured to the base of the instrument movement and project through openings in the rear wall of the case 9. The instrument shown in Figs. 2 to 5 is a wattmeter having ten terminals 14, the additional ter-

minals 15 being provided for lamps (not shown) which illuminate the scale plate 16 of the instrument. The construction of this instrument and its case is typical of that employed for voltmeters, 5 ammeters, frequency indicators and other electrical measuring instruments which may be mounted on the racks 1.

Flanges 17, preferably of channel form, are welded to the edges of each rack at its rear face 10 and are provided with openings 18 for receiving bolts to secure adjacent panel strips together to form the control panel for a plurality of electrical devices.

The racks 1, their attached flanges 17 and the 15 instrument cases 8 are preferably metallic, while the cover plates 8 may be conveniently formed of molded plastics. This permits the racks to be grounded and thus provides a "dead front" control board that eliminates all possibility of danger 20 to the operator.

The construction of the connecting panel and a 25 typical arrangement of the circuits established thereto are shown in Figs. 6 and 7. The particular circuit arrangements are appropriate for a control unit such as the panel strip shown at the right of Fig. 1, in which the upper instrument 30 may be a kilowattmeter W, the next lower a voltmeter V, and the lower three instruments are ammeters A¹, A², and A³. These instruments will be recognized as the group commonly employed for observing the operating conditions of a three phase generator or transmission line.

The connecting panel 20 comprises a molded 35 insulating plate having bolts 10 secured at the corners thereof for attaching the plate to the rack 1, the heads of the bolts being countersunk and threaded to receive the bolts by which the cover plate 6 is secured to the connecting panel. Two sets of four voltage terminals 21 are mounted, in vertical alignment, on and project through 40 the panel 20. At the lower portion of the panel, two sets of six current terminals 22 extend through the panel in vertical alignment and, as will be explained hereinafter, a third set of six 45 current studs project from the front face of the panel. The instrument connections are made to the upper terminals of each set, and the connections to the transmission line are made to the lower terminals of each set. At the front 50 of the panel 20, the vertically aligned terminals are connected by clips.

With this particular arrangement of instrument and transmission line terminals, the circuit connections are established in the usual manner 55 and it is believed that the following general description of the circuits established will be sufficient, without a detailed description of each connecting wire, to make clear the advantages of this panel construction. In Fig. 6, the transmission line or leads from the generator are identified by the characters L₁, L₂, L₃, and N. Voltage 60 transformers T are arranged in the usual manner with their primary windings connected between the lines L₁, L₂, L₃, respectively, and the neutral wire or ground N, the respective secondary windings being connected between the lower set of voltage terminals 21 and ground N. The several 65 terminals 21 are preferably identified, on the panel, by legends 1, 2, 3, and N, the fourth terminal "N" being connected to the grounded line N.

Current transformer windings S are arranged 70 on three lines L₁, L₂, L₃, and connected between the ground or line N and the alternate terminals, labeled S₁, S₂, and S₃, respectively of the lower 75 set of current terminals 22. The remaining ter-

minals of this lower set, labeled L₁, L₂, L₃, respectively, are connected to each other and to the ground or line N.

When these connections are made to the panel 20 and the connecting strip properly applied at the face of the panel 20 to join vertically aligned terminals of the voltage and current group, as indicated by dotted lines in Fig. 6, the several ammeters are properly connected to indicate the current flow on each line, the voltage between the 10 load lines and ground, and the kilowatt load on the line or generator. In the particular installation shown in Fig. 6, it will be noted that no connection is made to the instrument terminal 21 that is connected to the transformer on line L₂. 15 When a reactive kilovoltmeter is employed in place of, or in addition to the kilowattmeter, a connection is made, in the usual manner to this terminal.

It is to be noted that all of these connections 20 are made at the back of the connecting panel 20 and that, in practice, all instruments are mounted on the frames 1 and all connections are made between the instruments and the panel 20 in the shop. This permits a complete testing and calibration of the panel assembly before it is shipped 25 to its place of use. When the panel strip, or a group of panel strips, arrives at the generating plant or factory, the only electrical connections 30 to be made are those to the instrument transformers.

The advantages to be obtained by use of the described type of connecting panel will be apparent from Fig. 7 which illustrates the circuit connections, established at the face of the control 35 board, for calibration of the several instruments. The described arrangement of terminals 21 and 22 makes it possible to test the entire panel assembly without breaking any of the circuit connections at the rear of the panel. In Fig. 7, 40 the permanent wiring of the panel strip is shown in light lines and the wiring between the connecting panel and the testing equipment is shown by heavier lines.

The first step in testing the accuracy of the 45 several instruments is to short circuit the several current transformer windings S by clips 23 which, as shown in Fig. 8, are normally stored within the cover plate 6. These clips 23 are connected between the groups of terminals S₁ and L₁, S₂ and L₂, S₃ and L₃, of the third set of current terminals 50 24 (previously mentioned) which are connected to the lower set of current terminals 22 by the several connecting clips 25. After the application of the short-circuiting clips 23, the clips 26 which 55 normally connect the vertically aligned pairs of terminals 22 are removed and two of these clips are connected across the upper set of terminals 22 which are in vertical alignment with terminals 24 labeled L₁, S₂ and L₂, S₃, respectively. The clips 27 which normally connect the vertically aligned pairs of voltage terminals 21 are then removed, and two of the clips are then connected between the three upper voltage terminals 21 60 which were previously connected to the high voltage terminals of the several voltage transformers T.

It is to be noted that none of the connections 65 between the several instrument transformers T and S are broken, but the removal of clips 26 and 27 from their normal positions breaks the circuits between the transformers and the instruments. The replacement of certain of these clips in the positions indicated connects all of the 70 voltage terminals of the voltmeter V and watt- 75 meter T.

meter W in parallel, and connects all of the current windings of the wattmeter in series with the three ammeters A^1 , A^2 , and A^3 .

With these connections established a testing set including an ammeter A , a voltmeter V^1 , wattmeter W^1 and load box L may be appropriately connected to the instrument terminals at the face of the connecting panel 20 . As shown in Fig. 7, the instruments may be checked from any convenient source 30 of alternating current which may be a generator feeding a line 31 , 32 . A connection is made from one side 31 of the source 30 to the joined high voltage instrument terminals 21 and to the instrument current terminal 22 that was previously joined to the high voltage side of the current transformer winding S on line L . The terminal N of the voltage group 21 is connected to an adjustable tap 33 on a voltage divider 34 that is shunted across the source 30 and the standard voltmeter V^1 , and the voltage winding of the standard wattmeter W^1 , are also connected between the tap 33 and the lead 31 from the source.

From the upper instrument terminal 22 of the vertically aligned group labeled L_2 , a connection is made through the standard ammeter A to the current winding of the standard wattmeter W^1 , and then to one terminal of the adjustable load box L . The other terminal of the load box is connected to the line 32 from the source 30 .

With the establishment of these connections between the testing equipment and the connecting panel 20 , the current flow through the windings of the several instruments is indicated by the ammeter A , the voltage across the voltmeter V and the voltage winding of the panel kilowattmeter W is the same as that across the standard voltmeter V^1 , and the total load on the kilowattmeter is measured by the standard wattmeter W^1 . All of the instruments on the panel strip may therefore be readily and quickly checked without breaking any of the circuit connections at the back of the panel. In the event that a defective instrument is located, the instrument movement 12 may be removed by disconnecting the wiring to the instrument terminals 14 and the screws 13 which retain the movement within the casing 9 .

As distinguished from the known types of miniature control boards, the invention presents the mechanical advantage of localizing all instruments and control devices associated with a particular electrical unit upon a single panel strip which may be readily assembled with similar panel strips to form a complete control board. From an electrical view point, the invention provides a convenient means for checking the measuring instruments without necessitating any changes in the wiring of the control board.

I claim:

1. In a control board for electrical apparatus, a vertically disposed skeleton strip having a plurality of aligned openings, instrument cases inserted into a plurality of said openings from the face of the strip and having flanges secured to said strip to constitute the sole support for said cases, instrument movements secured in the several cases, and cover plates secured to each of said cases to complete the housings for the several instrument movements.

2. In a control board for electrical apparatus, a metal plate comprising narrow side strips between which narrow cross bars extend to provide a plurality of vertically aligned openings, instru-

ment cases extending through said openings from the face of said frame and having peripheral flanges overlying and secured to said plate to constitute the sole support for said cases, instrument movements in and supported by said cases, and cover plates for said instrument movements, said cover plates overlying and concealing the peripheral flanges of said cases.

3. The invention as set forth in claim 2, wherein flanges are secured to the rear of the side strips of said frame, said flanges providing means for securing the said frame to similar metallic frames.

4. In a control board for electrical apparatus, a plurality of substantially identical skeleton plates having their lateral edges secured to each other, each of said plates having a plurality of vertically aligned openings of uniform size, a plurality of indicating and control devices interchangeably receivable in said openings, means mounting said devices in certain of said openings and supporting the said devices solely from said plates, and cover plates secured over said openings and the devices mounted therein.

5. In a control board for mounting the indicating and control devices employed with a plurality of electrical machines, a skeleton plate for each machine, means securing the plates together with the lateral edges thereof in alignment, said plates being of identical construction and each having vertically aligned openings of uniform size, a plurality of instrument and control devices to be associated with each machine, and adapted to be received in said plate openings, the number of openings of each plate being not less than the maximum number of instrument and control devices required for any one of said machines, whereby all instrument and control devices for each machine may be mounted on one plate, and means for supporting solely by each plate the instrument and control devices mounted thereon.

6. The invention as set forth in claim 5, wherein each of said devices is inserted in its plate opening from the front face of the plate and includes a flange overlying the said plate, in combination with cover plates supported from said skeleton plates and overlying the respective devices.

7. The invention as set forth in claim 5, wherein each of said devices is inserted in its plate opening from the front face of the plate and includes a flange overlying the said plate, in combination with cover plates supported from said skeleton plates and overlying the respective devices, and dummy cover plates for covering those plate openings in which devices are not mounted.

8. In a control board for electrical apparatus, a vertically disposed skeleton plate having a plurality of vertically aligned openings, instrument cases inserted into a plurality of said openings from the face of the frame and having flanges secured to said plates to constitute the sole supports for said cases, the rear walls of said cases having openings therein, instrument movements secured in and supported by the several cases, said instrument movements having terminals extending through the said openings thereof, and a cover plate secured to each of said cases to complete the housing of the several instrument movements.

RAYMOND T. PIERCE.
